UNITED STATES PATENT OFFICE.

JACOB LIPS, OF NIEDER-URDORF, SWITZERLAND.

GEARING.

1,242,004.

Specification of Letters Patent. Patented Oct. 2, 1917.

Application filed November 28, 1916. Serial No. 133,389.

To all whom it may concern:

Be it known that I, JACOB LIPS, manufacturer, a citizen of the Swiss Confederation, residing at Nieder-Urdorf, Canton Zurich, Switzerland, have invented new and useful Improvements in Gearing, of which the following is a specification.

The object of the invention is to provide an improved mixing and kneading machine, principally intended for mixing flour and water and kneading the dough.

According to the invention two kneading implements, rotatably mounted on crank pins in a manner which is not in itself novel, are provided with arms, and these arms, placed crosswise, are connected by links to a fixed stud, by which part of the stress due to the kneading operation is borne.

The invention is illustrated in the accompanying drawings showing one form of construction,

Figure 1 being a vertical section,

Fig. 2 a front view, and

Fig. 3 a horizontal section on the line 25 A—B of Fig. 1,

Figs. 4 and 5 are detail views of the machine.

In the drawings 1 designates the frame, in which are mounted two parallel, horizontal shafts 2 and 3, each carrying a gear wheel 4. The wheels 4 are meshed with each other, and one of them is driven by a gear wheel 5. Each wheel 4 has a crank pin 6, upon which is rotatably mounted a sleeve 7 of a kneading head, having an arm 8. The arms 8 cross each other and are both connected by links 9 to a stud 10 fixed to a part 11 of the frame. Each kneader also has a kneading arm 12 fitting into a groove in the kneader head and having a kind of hook 13 at the top, engaging over the part 15 of the head. A pin 14 passes through the head and the arm 12, and is made fast by means of a catch 15¹. Axial movement of the kneader on the 45 crank pin 7 is prevented by a nut and washer

16. The pan 18 is mounted by means of a pivot 17 on a carriage 19 having a table 20, on which are two studs 21. Upon the frame 1 there are two pivots 22 for eccentric abutments 23 having handles 24. These abutments lie in the path of the studs 21 when the carriage with the bowl is moved to and from the machine, and they are so placed in relation to the studs that they can only be rotated into position to retain the carriage 50 when the bowl is in the proper position in relation to the kneaders. The bowl is rotated by means of bevel gear.

When the wheels 4 are driven the kneaders rotate with the crank pins 6, and the stress 60 due to the work is in part borne by the stud 10. When the stress is greatest the parts are positioned most favorably to bear it, so that a strong machine can be constructed of comparatively light design.

Having now particularly described and ascertained the nature of my said invention, and in what manner the same is to be performed, I declare that what I claim is:

In combination, a frame, a pair of parallel shafts mounted in the frame, a gear wheel mounted on each shaft, said gears being in meshing relation, a crank pin extending from each gear wheel, a shaft disposed above and in a central plane between the parallel shafts, arms pivoted on the crank pins and extended upwardly and across each other, a link pivotally connected to the upper end of each arm, said links being pivotally supported upon the centrally disposed shaft above the gear wheels, means for rotating one of the gear wheels, and rods mounted on the crank pins and actuated thereby.

In testimony whereof I affix my signature in presence of two witnesses.

JACOB LIPS.

Witnesses:

FRITZ ULI,
CARL GUBLER.
